H. W. LEE & G. H. WEEDMAN.
MINE ALARM INSTRUMENT.
APPLICATION FILED FEB. 11, 1911.

1,018,328.

Patented Feb. 20, 1912.

UNITED STATES PATENT OFFICE.

HENRY WHITE LEE AND GEORGE HENRY WEEDMAN, OF MOUNT MORGAN,
QUEENSLAND, AUSTRALIA.

MINE-ALARM INSTRUMENT.

1,018,328.

Specification of Letters Patent. Patented Feb. 20, 1912.

Application filed February 11, 1911. Serial No. 607,916

To all whom it may concern:

Be it known that we, HENRY WHITE LEE, electrician, and GEORGE HENRY WEEDMAN, electrical fitter, subjects of the King of Great Britain and Ireland, both residing at Mount Morgan, in the State of Queensland, Commonwealth of Australia, have invented new and useful Improvements in Mine-Alarm Instruments, of which the following

10 is a specification.

The object of this invention is to provide a speedy and effective alarm to be actuated electrically or otherwise for the purpose of, in case of ground falls, warning miners who are in or upon the mine, or for like purposes.

By the devices hereinafter described, the slightest movement in the ground can be immediately signaled by means such as alarm bells or electric lights or both in or to the various parts of the mine. In mines without electric apparatus the warning may be by mechanical devices such as bells and where electricity is used the signaling by red 25 or other lights as well as bells or other modifications will be preferably adopted as being more effective.

The alarm instrument is constructed of a wire circuit and several telescopic or slidably jointed pipes or members of size and description to suit open chambers or drives where there is any danger of a creep or movement of the roof.

In the drawings which accompany and 35 form part of this specification Figure 1 is a view of the alarm apparatus fitted in a drive of a mine; Fig. 2, an enlarged vertical section of the apparatus showing the telescopic tube; Fig. 3, a vertical section of the top terminal; Fig. 4, a plan of same; Fig. 5, a vertical section of the bottom terminal; Fig. 6, a plan of same.

A is the fork which abuts against the roof of the drive or chamber.

45 B is the upper pipe member to which the fork is attached. C is a second pipe member.

D is a slot formed in pipe C to receive pin E which is secured to pipe B.

F is a terminal bearing ring secured to pipe B.

G is a terminal bearing ring secured to pipe C.

55 H, H are thumb screws for adjusting the terminal rings.

I is a spring attached to the bottom of pipe B and J is a rest for the same.

K is a wood tube in which the exterior of C slidably fits and L a thumb screw for adjusting the height of pipe C in K.

A tripod stand is provided having the ring M in which the pipe K slides, and N is a thumb screw by which the position of K is adjusted higher or lower as desired.

O is a switch for controlling the signal 65 circuit and PP PP PP are wires leading to electric lights and bells arranged in various parts of the mine.

In operation the members are slidably adjusted and secured by the thumb screws so 70 that the fork or any other suitable top portion is sprung into or impinges against the roof of the chamber or drive. Any movement of the ground overhead causes the fork or top to press the upper terminals into 75 or against the lower terminals thus establishing electric contact and causing signals to operate such as lamps to glow and bells to ring to warn the persons employed. Any number of alarms may be connected together 80 and in parallel if desired or they may be worked singly. A bell battery of two cells may be conveniently used being placed anywhere near the alarm and does not require much or any difficult attention. The terminal rings are of wood to insulate them 85 from the standard.

The upper members may be telescoped into bottom members and the tripod folded so that the whole apparatus can be easily 90 moved.

We claim:

1. In a mine alarm instrument, a pair of rods, one of said rods being arranged to extend within the other, a spring for holding 95 the inner rod in an extended position, an adjustable contact member carried by the inner rod, a second adjustable contact member carried by the outer rod, means carried by said inner member for engaging one of the mine walls, and means in engagement with the opposite wall for supporting said outer member.

2. In a mine alarm instrument, a support in engagement with one of the mine walls, 105 a hollow rod adjustably secured to said support, contact members adjustably secured to said hollow rod, a second rod arranged to enter said hollow rod, said second rod being provided with means for engaging 110

the other of the mine walls, adjustable contacts carried by said second named rod arranged to engage the first named adjustable contacts, and a spring within said hollow 5 rod for holding said inner rod in engagement with one of the walls.

In testimony whereof, we have signed our

names to this specification in the presence of two subscribing witnesses.

HENRY WHITE LEE.

GEORGE HENRY WEEDMAN.

Witnesses:

ROBERT GAMBLE BROWN,

WILLIAM CATHRO TAIT RUSSELL.
